DESIGN FOR A CAP

Elsie C. Hogg, Elizabeth, N. J.

Application December 12, 1941, Serial No. 104,604

Term of patent 3½ years

To all whom it may concern:

Be it known that I, Elsie C. Hogg, a citizen of the United States, residing at Elizabeth, in the county of Union and State of New Jersey, have invented a new, original, and ornamental Design for a Cap, of which the following is a specification, reference being had to the accompanying drawing, forming part thereof.

In the aforesaid drawing:

I claim:

The ornamental design for a cap, as shown.

ELsie C. Hogg.
